Be it known that I, GABRIEL GUTLOHN, a citizen of the United States, residing at Philadelphia, in the county of Philadelphia and 5 State of Pennsylvania, have invented a certain new and useful Design for a Hat-Trimming, of which the following is a specification.

My invention has relation to ladies' and misses' head-wear and has for its object the 10 provision of a unique and attractive design for a hat-trimming, the same consisting of a number of limbs or paw-like members of an animal, each such limb or member terminating in claws and projecting, leaf-like, from a 15 common stalk or stem, the whole being sur-
